WINDOW

Casper F. Hanson, Albert Lea, Minn., assignor
to Olson Manufacturing Company, Albert Lea,
Minn., a corporation of Minnesota

Application April 6, 1936, Serial No. 72,867

7 Claims. (Cl. 189—69)

This invention relates to window constructions particularly for use in barns, warehouses, shops, etc., but may also be installed in garages, dwellings, and other buildings where the particular features thereof may be desired or employed to advantage; and the main object is to provide a novel, efficient, and practical arrangement of frame and sash wherein the sash is swingably and slidably associated with the frame and provided with improved means for adjustably securing the sash in adjusted positions with respect to such swinging and sliding movements to effect various sizes and arrangements of frame openings. Further and more detailed objects and advantages will be disclosed in the course of the following specification, reference being had to the accompanying drawing, wherein:

Fig. 1 is an elevation of my improved window construction as seen from the inside of a building and with the sash in closed position.

Fig. 2 is a sectional elevation on line 2—2 in Fig. 1.

Fig. 3 is a sectional elevation similar to Fig. 2, but with the sash in partly swung open position, the lower portion of the view being broken away.

Fig. 4 is a sectional elevation similar to Figs. 2 and 3, but showing the sash in a more advanced open position.

Fig. 5 is an enlarged detail section on line 5—5 in Fig. 2.

Fig. 6 is a perspective elevation of a portion of the structure, with glass panes removed and other parts broken away, this view illustrating the relative arrangement of various members when the sash is in both tilted and raised position.

Fig. 7 is an enlarged detail sectional plan view on line 7—7 in Fig. 4, but with portions of the sash stay or securing arm broken away.

Fig. 8 is an enlarged detail section illustrating the grip connection between the stay and sash when the sash is in the raised position shown in Fig. 6.

The frame and sash parts of the device may be made of either wood or metal but I have here illustrated only a metal construction inasmuch as metal especially lends itself to a window of this design, being light, strong, and easily installed, and to this end I employ iron or steel bars which are welded or otherwise suitably connected and are of angle or T-iron material to further assist in rigidifying the respective units.

Referring to the various figures of the drawing particularly and by reference characters, A designates generally the rectangular window

frame which is secured in the building wall and includes a sill 9, stiles or side bars 10, and an upper cross bar 11. The members 9, 10, and 11 are all preferably formed with outer edge flanges 12 to facilitate securing the frame in the wall opening, and bars 10 and 11 are all provided with inner flanges 13 against which the outer face of the sash stops when closed. The sill 9 also has an integral inner flange, 14, which, however, is spaced inwardly from the plane of flanges 13, 10 as shown in Figs. 2, 4, 5, and 7, to form a recess 15 to tiltably and releasably receive the flange 16 of the sash designated as B.

The sash unit B is of rectangular construction to fit within frame A and into closing engagement outwardly against flanges 13. The side bars 19 and top and bottom bars 20 and 21 of the sash are connected by mullions 17 forming the openings in which lights or panes 18 are secured in any suitable manner. The upper end of the sash B may be swung inwardly from the frame A, as shown in Figs. 3 and 4, the lower end pivoting on the upper edge of sill flange 14. This arrangement allows ventilation through an upper opening (between bars 11 and 20), and triangular side openings, while the angle of the sash tends to deflect rain and snow, and the overlap of sash flange 16 with respect to sill flange 14 serves to prevent water leakage inwardly over the sill.

The sash is releasably secured by a stay or lock frame C, which is generally U-shaped in form having angle iron side arms 22 connected by a cross bar 23. The bar 23 may be of any suitable cross sectional form and has for its objects to insure simultaneous movements of the arms 22, to cooperate with the arms to form grips for engaging the sash, and to serve as a handle for manipulating the stay frame.

The side or vertical flanges of the arms 22 have their ends, opposite from bar 23, pivotally secured, as at 24, to the inner upper ends of the stiles 10. The other flanges of the arms are inwardly notched, as at 25, to selectively receive the ends of the upper flange of sash rail 20 (see Fig. 3), to thereby secure the sash in more or less open, inwardly tilted positions. The sash is released from the notches 25 by lifting the stay frame to approximately horizontal positions at which time the sash may be moved freely under the notched flange. It may here be noted that when the sash is in closed position, the stay frame drops down in front of the sash, as in Figs. 1 and 2, and at such time the ends of the notched stay flanges adjacent pivots 24 effective-

ly lock the sash in the frame A to prevent opening of the window from the outside of the building.

In addition to the inward tilting and adjustments of the sash I also provide for vertical adjustments, as shown in Fig. 6, to thereby effect substantially greater window opening clearance when the same is desired. As previously noted the sash B is not pivotally anchored or attached to the frame A, but merely seats in the recesses 15 while flange 16 overhangs sill flange 14 to tilt thereon, the swinging connection being maintained by the weight of the sash only.

When it is desired to elevate the sash, as shown in Fig. 6, to obtain clearance under the sash also, then the sash is first released to the position shown in Fig. 4, at which time it rests against the stay frame bar 23 and is in position to be lifted upwardly through inwardly opposed recesses 26 formed in the ends of the stay frame C between the bar 23 and outer lips 27 of the notched flanges of bars 22. The size of the openings 26 is such that the sash may be freely lifted or pushed upwardly therethrough. The opening is sufficiently restricted, however, so that when the sash is released its weight and the weight of the stay frame will tend to spread the lower angle therebetween, producing a bite or grip on the sash between lips 27 and bar 23, as illustrated in Fig. 8. As the stay frame C is free to move on pivots 24 under its own weight, it will be self-adjusting on the sash as the latter is pushed upwardly. When it is desired to lower the sash it is only necessary to first slightly raise the stay frame, to release the bite or grip, and then hold it so raised with one hand while the other hand partially or completely lowers the sash under gravitational action. To insure proper guiding action of the lower end of the sash with respect to the stiles 10, when the sash is raised and lowered, it is provided at its lower outer corners with fingers 28 which are welded or otherwise suitably secured thereto and guide against the outer faces of stile flanges 13. The recess formed by these fingers must of necessity be sufficiently large to permit tilting of the sash without binding.

It is understood that suitable modifications may be made in the structure as disclosed, provided such modifications come within the spirit and scope of the appended claims. Having now therefore fully illustrated and described my invention, what I claim to be new and desire to protect by Letters Patent is:

55 1. The combination with a window frame, of a sash mounted for vertical adjustment in the frame and with its upper end tilttable inwardly on a horizontal axis to open the window, a generally U-shaped stay member having its arms pivotally secured to the frame adjacent the sides thereof and with a connecting cross bar extending transversely of the sash, said stay member arms having opposed parts engageable with opposite surfaces of the sash to releasably grip and secure the same in vertically and tiltably adjusted open positions.

2. The combination with a window frame, of a sash mounted in the frame for vertical adjustment therein and for tilting movement on a horizontal axis, and stay arms pivotally secured to the frame and engageable with the sash to secure it in selected tilted positions, said arms being operative to lock the sash in closed positions, and said arms having recesses to slidably receive and frictionally grip side parts of the sash to sup-

port the sash in selective vertically adjusted positions.

3. The combination with a window frame, of a sash mounted in the frame for vertical adjustment therein and with its upper end swingable inwardly from the frame on a transverse horizontal axis, a generally U-shaped stay member extending across the inner side of the sash and with its arms pivotally attached to the frame near upper corners thereof, said stay members having means for slidably engaging the sash and for producing a position retaining grip thereon under the action of gravity tending to angularly spread the stay member with respect to the sash.

4. The combination with a window frame, of a sash mounted in the frame for vertical adjustment therein and with its upper end swingable inwardly from the frame on a transverse horizontal axis, a generally U-shaped stay member pivoted to the frame and passing laterally and inwardly of the upper end of the sash to embrace the same, said stay member being swingable downwardly into a depending position against the sash, when the latter is closed, to releasably lock the same, and means at the outer end of the stay member for slidably receiving and frictionally engaging the sash to secure it in adjusted positions.

5. The combination with a window frame, of a sash mounted in the frame for vertical adjustment therein and with its upper end swingable inwardly from the frame on a transverse horizontal axis, a generally U-shaped stay member pivoted to the frame and passing laterally and inwardly of the upper end of the sash to embrace the same, said stay member being swingable downwardly into a depending position against the sash, when the latter is closed, to releasably lock the same, and means at the outer end of the stay member for slidably receiving and frictionally engaging the sash to secure it in adjusted positions, and means connecting the sash with the stiles of the frame adjacent the tilting axis of the sash to maintain pivotal and sliding engagement of the sash with respect to the frame.

6. The combination with a window frame, of a sash mounted in the frame for vertical adjustment therein and with its upper end swingable inwardly from the frame on a transverse horizontal axis, a generally U-shaped stay member pivoted to the frame and passing laterally and inwardly of the upper end of the sash to embrace the same, said stay member being swingable downwardly into a depending position against the sash, when the latter is closed, to releasably lock the same, and means at the outer end of the stay member for slidably receiving and frictionally engaging the sash to secure it in adjusted positions, the sill of the frame having an upstanding longitudinal flange, and the lower rail of the sash having a flange adapted to outwardly overhang the sill flange.

7. The combination with a window frame, of a sash mounted in the frame for vertical adjustment therein simultaneously with tilting movement on a horizontal axis, and means attached to the frame and influenced by the weight of the sash to adjustably grip the sides thereof at selected points above the tilting axis to support the sash in vertically adjusted positions, said means comprising a pair of arms each being pivoted at one end to the frame and having its other end provided with a recess engaged by a side bar of the sash.
